United States Patent Office.

PHILIP ELY, OF NEW YORK, N. Y., ASSIGNOR TO J. M. KEEP & CO.,
OF SAME PLACE.

Letters Patent No. 63,148, dated March 26, 1867.

IMPROVEMENT IN STEAM MOTOR FOR TOYS.

The Schedule referred to in these Letters Patent and making part of the same.

TO ALL WHOM IT MAY CONCERN:

Be it known that I, PHILIP ELY, of the city, county, and State of New York, have invented a new and improved Steam Motor for Toys; and I do hereby declare that the following is a full, clear, and exact description thereof, which will enable others skilled in the art to make and use the same, reference being had to the accompanying drawings, forming part of this specification, in which—

Figure 1 is a side sectional view of my invention, taken in the line $z z$, fig. 2.

Figure 2 is a plan or top view of the same.

Similar letters of reference indicate like parts.

This invention relates to a simple and economical steam motor for operating toys, and consists of a peculiar adaptation of the most ancient rotary engine (Hero's) for that purpose.

A represents a lamp, alcohol or other material being used in it. This lamp may be constructed in any proper manner, and it has a vertical rod, B, fitted centrally in it. C is the boiler, which may be constructed of sheet metal and of conical form. This boiler is provided with a concave bottom, in the centre of which is a conical projection, b, which receives the pointed end of the rod B, and supports or forms the bearing for the boiler, so that it may rotate freely thereon, directly over the lamp A, as shown in fig. 1. To the upper part of the boiler there are attached one or more tubular horizontal arms D, which communicate with it. These arms are of bent or curved form, as shown clearly in fig. 2, and it will be seen that when the boiler is supplied with water and the lamp A lighted, steam will be generated in the boiler C, and escape through the arm or arms D, and by reaction in its passage through D, rotate the boiler, from which any revolving toy, E, may be driven by a belt, F. In fact, toys having various movements may be operated by this motor. The device may be very cheaply constructed, and will form a very amusing and instructive toy for children.

I claim as new, and desire to secure by Letters Patent—

The revolving boiler C, provided at the centre of its concave bottom with a conical projection, b, which is fitted on the rod B, forming the bearing for the boiler, and having at its upper end the arms D, and adapted to bear the strap or band F, by which motion is communicated to the toy E, as and for the purpose described.

PHILIP ELY.
